SASH CONSTRUCTION

Victor William Braybrook, Hounslow, England

Application March 5, 1946, Serial No. 652,065
In Great Britain March 8, 1945

5 Claims. (Cl. 20—56)

1

This invention relates to windows of the casement type.

The hinged casement sash of the type of casement wood window which is popular at the present time is at present normally provided with a rebate to receive the glass and putty or the like, and also with a rebate forming a lip for weatherproofing purposes which overlaps part of the window frame, that is to say the fixed part in which the casement sash is hinged. This double rebated formation considerably weakens the casement sash and renders it more liable to warp. Further in connection with fixed lights there is a trend towards direct glazing into the window frame, to economise timber, instead of, as formerly, providing fixed casement sashes to carry the glass. This means that in a window, for openings having the same size, there will be a larger area of glass in the fixed lights (where there is no casement sash) than in the opening lights (where there is a casement sash) so that neither the vertical nor horizontal glass lines in the fixed and opening lights will be in alignment with each other, which is very unsightly. The main objects of this invention are the removal, as far as possible, of all these disadvantages.

According to the present invention the rails and stiles of a casement sash are built up of main members and inner members, suitably held together, the main members normally resting against the external face of the casement frame, and the inner members which are fitted to the inner perimeter of the main members being only partly inset in the plane of the casement sash, so that they set inwards from the external face of the main members leaving the equivalent of a rebate for glass in the casement sash, and project internally and enter a rebate in the window frame.

The rails and stiles formed in this way are preferably of timber so arranged that any tendency in the inner members to warp is as far as reasonably possible at right angles to any such tendency in the main members.

It will be convenient and facilitate this arrangement if the depth of the inner members (that is their dimension at right angles to the plane of the glass) is the same as the width of the main members (that is their dimension parallel with the plane of the glass), whereby the inner and main members can be cut from similar pieces of timber of the same thickness, the dimension they have in common being the thickness of the timber.

Referring to the drawings which form a part of this specification:

2

Figure 1 is a vertical sectional elevation through a casement window, embodying a transom.

Figure 2 is a vertical sectional elevation through another casement window without a transom.

Figure 3 is a vertical sectional elevation through a window sill.

Figures 4, 5, 6 and 7 are fragmentary horizontal sections, looking downwards, showing the invention applied to alternative types of casement windows.

Figure 8 is a vertical sectional elevation through a similar casement window to Figure 2 showing double glazing.

Figure 9 is a vertical sectional elevation through a window frame showing double glazing.

Referring first to the figures generally, the parts of the window frame are denoted by heads 1, sills 2, transoms 3, mullions 4 and jambs 5. In the window frame are formed rebates 10, adapted either to receive direct glazing or hinged casement sashes. The latter are built up of main members 11 enclosing approximately the same area for glass 15 as the area of glass resulting if direct glazing to the window is used. This can be most readily seen by comparing Figures 2 and 3, or Figures 8 and 9. The cutting dimensions of the glass can be identical even if the exposed areas of glass differ slightly. To the inner perimeter faces of these main members are secured inner members 12, by glueing or other means, with the assistance of grooves and tongues 13 or similar formations if required.

These inner members are set back from the external face of the main members so that they leave in effect glazing rebates, being of the same width as the glazing rebates in the fixed frame, and in depth the inner members extend internally at 14 beyond the internal face of the main members to fit into the rebates in the fixed frame. The timber for the inner and main members, it will be seen, can be cut so that any tendencies they may have respectively to warp

will be at right angles to one another when the members are assembled, so that the combined result will tend to resist warping. Metal angle section members are secured to the sashes or to the frames where desirable, as indicated at 20.

The various figures are intended to illustrate the application of the before-mentioned features of construction to some of the types of windows most commonly required.

Figure 1 shows a window in which there is a transom 3, the light above the transom being a top hung transom light whose hinges are indi-

cated at 21, while the lower light is a side-hung casement. It will be seen that the top light is built up of members 11, 12 in precisely the same way as the lower light. Figure 2 differs in that there is no transom; the side-hung casement extends the full height of the window. Figure 3 shows part of a similar sill 2 to that of Figures 1 or 2, but in this case the glass 15 is glazed direct into the frame to form a fixed light, and it will be seen that the glass area is substantially the same. In Figure 4 a side hung casement is shown alongside a fixed light. The side hung casement closes against the centre mullion 4. At the right-hand side of the figure, however, it will be seen that the glass 15 is fixed direct to the mullion.

It has been supposed up to the present in this description that the top and bottom rails, the hanging stile and the closing stile of the casement sash, or where the sash is not side-hung, the two stiles, the hanging rail and the closing rail, will all be constructed on the lines described. There are, however, certain circumstances where this will need to be modified. Figure 5 shows the case where two side hung casements meet as a pair without an intervening mullion, and here the closing stiles 21 are formed with angle-pieces 22, or otherwise arranged in any known or convenient manner, so that they can close one on to the other. Figure 6 shows another case where the closing stile 21a of a side hung casement adjoins the side of a fanlight, transom light, or top hung casement 23, where it will be apparent that the members 21, 23 have to be formed so that they do not foul each other.

Figures 7 to 9 show the inner members 12 of the sashes, (in the case of opening lights), or the window framing members (in the case of direct glazing), arranged to carry an additional pane of glass, the two separate thicknesses of glass with an air space between them serving as is well known to improve the insulation of the window as regards heat and sound. Figure 7 is a similar view to Figure 4, showing an opening casement at the left hand side of the figure and direct glazing in the frame at the right hand side. The inner pane of glass is secured by fillet 24 secured to one of the sash stiles instead of the inward extension 14, so that by removing the fillet 24 the glass can be slid out. In the direct glazing the inner pane is secured by similar fillets 25, one of which may be quickly removed by withdrawing fixing screws 26. The cavity between the two panes of glass may be drained by means of suitable weep holes 27. Figure 8 is a similar view showing a window frame only in which there is this double glazing and Figure 9 is a similar view to Figure 3 showing double glazing direct to the frame.

Having now described my invention what I claim as new and desire to secure by Letters Patent is:

1. A window comprising a frame having a rebate therein, a casement sash mounted in the frame, the rails and stiles of the casement sash including separate main members and inner members, means securing said main and inner members

together, the main members normally resting against the outer face of the frame and being wholly located without the plane of the window frame, each inner member being secured to each main member so that the outer face thereof is located within the plane of the casement sash to provide a rebate for a transparent panel rearwardly of the outer face of the casement sash and the inner face of each inner member extending inwardly of the inner face of each main member for forming a projection entering the rebate in the window frame.

2. A window construction as claimed in claim 1 wherein each inner member is in facial engagement with the inner side face of each main member and the means securing the inner member and the main member together comprises a tongue and groove assembly on said member.

3. A casement sash adapted to be inserted into a window frame having a rebate therein comprising parallel side rails and stiles and means connecting the side rails and stiles, each of said side rails and stiles comprising a main member and a secondary member adapted to be located in facial engagement with the inner side face of each main member, complementary means on said main member and secondary member to secure said members together, each secondary member being so secured to the main member that the outer face thereof is within the plane of the sash to provide a rebate for a glass panel inwardly of the outer face of the main member, and the inner face of each secondary member projecting beyond the inner face of each main member to form a projection entering the rebate of the window frame.

4. A rail element for use in a casement sash of the type for mounting in a window frame having a rebate therein comprising a main member, a secondary member disposed on the inner face of said main member and extending longitudinally thereof, complementary means on said main member and secondary member for securing said members together, the outer face of said secondary member being located within the plane of said main member to provide a rebate inwardly of the main member, and the inner face of said secondary member extending beyond the inner face of the main member to form a projection.

5. A rail as claimed in claim 4 wherein the complementary means securing the main and secondary members includes a tongue on the main member, and a groove in the secondary member.

VICTOR WILLIAM BRAYBROOK.
